UNITED STATES PATENT OFFICE.

CHARLES M. HYATT AND ROBERT C. PRUYN, OF ALBANY, NEW YORK,
ASSIGNORS TO THE EMBOSSED COMPANY.

IMPROVEMENT IN PICTURE-PUZZLES.

Specification forming part of Letters Patent No. 179,023, dated June 20, 1876; application filed
April 27, 1876.

To all whom it may concern:

Be it known that we, CHARLES M. HYATT and ROBERT C. PRUYN, both of the city and county of Albany, in the State of New York, have invented a new and Improved Spelling-Puzzle, which invention is fully set forth in the following specification, reference being had to the accompanying drawing, in which—

Figure 1 represents the obverse side of our puzzle when put together. Fig. 2 shows the reverse side thereof.

Similar letters indicate corresponding parts.

Our invention consists in the combination of two or more cards or blocks containing parts of a picture, and parts or the whole of a letter, word, or figure on two opposite sides thereof, the whole being arranged in such a manner that when the cards or blocks are properly put together one side thereof shows a complete picture, while the other side shows the name or definition of such picture, and by this means we obtain a puzzle or toy which is both amusing and instructive.

In the drawing, the letter A designates a series of cards or blocks, one of whose sides contains part of a picture, (see Fig. 1,) consisting, in this example, of hounds chasing a deer. The opposite or reverse sides of each of these cards or blocks contain letters or parts of words, (see Fig. 2,) which together constitute a sentence, showing the name or definition of the picture referred to. The said letters or words and the said picture are so arranged relatively to each other that, when the cards or blocks A are put together so as to show the picture in its complete form on one side thereof, the name or definition of the picture is shown on the reverse side; and on

the other hand, when the cards or blocks are put together for the purpose of spelling the name of the picture, the latter will be seen by turning over the blocks.

We prefer to print or mark the picture, as well as its name or definition, directly on the cards or blocks; but they can be produced in a variety of other ways well known to those skilled in the art.

When our invention is applied to blocks, two pictures and their names or definitions may be produced thereon, each picture and its definition, however, being arranged on two sides which are diametrically opposite to each other.

It is obvious that any selected picture or object can be substituted for the one shown without departure from our invention, and, moreover, figures or numerals can be used together with, or instead of, the letters or words to form the key.

What we claim as new, and desire to secure by Letters Patent, is—

A puzzle consisting of pieces of wood or other material, each piece having on one side a part of a picture, and on the opposite side part or the whole of a letter, numeral, word, or sentence, so that each side forms a key for the other, substantially as shown and described.

In testimony that we claim the foregoing we have hereunto set our hands and seals this 25th day of April, 1876.
